DRESSING MECHANISM

Arthur L. Stewart, Rochester, N. Y., assignor to
 Gleason Works, Rochester, N. Y., a corporation
 of New York

Application June 3, 1940, Serial No. 338,562

2 Claims. (Cl. 125—11)

The present invention relates to dressing mechanisms and particularly to mechanisms for dressing the side surfaces of grinding wheels such as are employed in the grinding of longitudinally curved tooth bevel and hypoid gears.

One object of the present invention is to provide a dressing mechanism which may be adapted readily to the dressing of any desired profile shape on a grinding wheel.

A further object of the invention is to provide a dressing mechanism that may be used to dress the greater portion of the height of an active side surface of a grinding wheel to one pressure angle and to dress the remaining portion of the height of said side surface of the wheel to either a greater or a lesser pressure angle.

Other objects of the invention will be apparent hereinafter from the specification and from the recital of the appended claims.

The present invention has wide application. It may be used for dressing grinding wheels of any desired shape. One particular use of the mechanism is in the dressing of annular grinding wheels such as are used for grinding in a generating operation the teeth of longitudinally curved tooth bevel and hypoid gears. Such a wheel ordinarily has opposite sides dressed to positive pressure angles. The opposite sides of such a wheel converge, therefore, toward the tip of the wheel with the result that the wheel is of relatively thin section near its tip. It has been found that because of this thin section, the wheel may deflect away from the gear tooth being ground, particularly when pinions are being ground, since only one side of a pinion tooth is ordinarily ground at a time. When this deflection occurs, the wheel does not remove an even amount of stock over the full height of the pinion tooth and more stock than is desired may be left near the roots of the teeth. During the generating roll, moreover, the wheel may wear away faster near its tip than over the rest of its height. This, too, tends to cause the wheel to leave on more stock than desired near the roots of the teeth of the pinions. The excess amount of stock left near the roots tends to produce an interference when the pinion is run with its mate gear and the pair may, therefore, be noisy. If the wheel is dressed, however, with smaller pressure angles adjacent its tip than along the rest of its height, the wheel will be more rigid near its tip and, moreover, the smaller pressure angle portion of the wheel surface will tend to relieve the tooth surface of the pinion near its root and this tendency will offset any tendency of the wheel to leave on stock due

to deflection or wear. Hence, tooth surfaces may be ground on the pinion which will not interfere with the mating tooth surfaces of the mate gear.

This is but one use of the dressing mechanism of the present invention. Other uses will immediately suggest themselves to those skilled in the art.

In the preferred construction of the present dressing mechanism, a pair of dressing tools are employed to permit of dressing simultaneously opposite side surfaces of a grinding wheel. Each tool is mounted to swing in an arcuate path across the side surface to be dressed and is adapted to be moved axially of its axis of swing during its arcuate movement, thereby to produce a modified shape on the profiles of the grinding wheel.

In the preferred construction, each tool is mounted on an arm that is secured to one end of an oscillatable shaft. A follower is secured to the opposite end of the shaft and the follower engages a fixed cam. As the shaft is oscillated, then, to move the dressing tool across the wheel surface, the shaft is moved axially, the extent and duration of its axial movement depending on the shape of the control cam. Thus by selecting a cam of suitable shape, any desired shape may be dressed on the grinding wheel.

In the drawings:

30 Fig. 1 is a part plan, part sectional view of a dressing apparatus built according to one embodiment of the invention for dressing the two sides of a grinding wheel simultaneously, and showing the dressing tools in engagement with a wheel to be dressed;

35 Fig. 2 is a developed sectional view through the apparatus taken on the line 2—2 of Fig. 1;

Fig. 3 is a developed view of a cam such as may be employed in this dressing apparatus for dressing a side surface of a grinding wheel to have one pressure angle for part of its height and a lesser pressure angle for the remainder of its height;

40 Fig. 4 is a view looking at the back end of one of the dressing mechanisms with the protecting cover removed and showing particularly the follower and control cam of this dressing mechanism; and

45 Fig. 5 is a diagrammatic view illustrating the operation of the dressing apparatus of the present invention.

In the drawings, W denotes the grinding wheel whose side surfaces are to be dressed. 10 denotes a dressing tool for dressing the outside surface of this wheel and 11 a dressing tool for

dressing the inside surface of the wheel. The dressing tool 10 is secured in any suitable manner in the free end of an arm 12 that is fastened at its opposite end to a shaft 14. The dressing tool 11 is mounted in any suitable manner in the free end of an arm 13 that is fastened at its opposite end to a shaft 15. The two arms 12 and 13 are suitably shaped so that the dressing tools carried thereby may be swung across the inside and outside surfaces, respectively, of the grinding wheel without the arms interfering with one another.

The shafts 14 and 15 are mounted in a housing 20 with their axes inclined to one another at an angle approximating the included angle between the major parts of the inside and outside surfaces of the grinding wheel. Each shaft is mounted in the support 20 for both oscillatory and axial movement.

The oscillatory movements of the two shafts are produced by reciprocation of a piston 22 which moves in a cylinder 23 formed in the housing 20. This piston 22 has rack teeth 24 and 25 cut into it at opposite sides. The rack teeth 24 mesh with the gear segment 26 which is clamped by means of a bolt 28 to the periphery of the shaft 14 at a point intermediate the ends of the shaft. The rack teeth 25 mesh with the spur gear segment 27 which is clamped by a bolt 29 to the shaft 15 intermediate the ends of that shaft. The piston 22 may be moved alternately in opposite directions to swing the dressing tools 10 and 11 back and forth across the side surfaces of the grinding wheel by any suitable means such as described, for instance, in the pending application of Ernest Wildhaber and Leonard O. Carlsen, Serial No. 304,150, filed November 13, 1939.

Formed integral with the shaft 14 at its rear end is an arm 30. The free end of this arm has its rear face formed to serve as a follower and this follower engages an arcuate face cam 32. This cam is fixedly secured in an end plate 34 which is fastened in any suitable manner to the housing 20.

Integral with the shaft 15 is an arm 31. The free end of this arm has its front face formed to act as a follower and this follower engages an arcuate face cam 33 which is secured by screws 34 (Fig. 4) to the housing 20.

The cams 32 and 33 may be of identical form. In Fig. 3, I have shown in development the form of cam which may be employed where it is desired to dress a grinding wheel so that each of its active side surfaces is of straight profile and one pressure angle for the greater portion of its height and of straight profile and smaller pressure angle for the remaining portion of its height. Such a wheel is shown in Figs. 1 and 5.

For dressing such a wheel, the control cam is formed with an arcuate projection 45 that is coaxial of the shaft 14 or 15 as the case may be, when the cam is in operative position, and that extends through an angle of 180° or less. The top land of this projection constitutes the control surface of the cam. In the case illustrated, the greater portion 46 of this control surface lies in a plane perpendicular to the axis of the shaft 14 or 15 with which the cam is associated, but a portion of the control surface, as denoted at 47, is slabbed off or inclined to the plane surface 46. While the free end of arm 30 or arm 31, as the case may be, is riding on the plane portion 46 of the corresponding control cam 32 or 33, during rotation of the associated

shaft 14 or 15, the tip of the corresponding dressing tool 10 or 11 simply swings in a plane perpendicular to the shaft 14 or 15. Thus the tool 10 will dress the portion 40 of the profile of the 5 outside active surface of the wheel, and the tool 11 will dress the portion 41 of the profile of the inside active surface of the wheel. When the free end of arm 30 or arm 31 rides on the inclined or slabbed off surface 47 of the associated 10 control cam, however, the corresponding shaft is moved axially so that the associated tool 10 or 11, as the case may be, dresses a surface on the wheel whose profile 42 or 43 is of less pressure angle than the profile 40 or 41. Thus surfaces 15 may be dressed on both the inside and outside of the wheel which are of one pressure angle for the greater part of their heights and of less pressure angle adjacent the tip of the wheel.

The free end of the arm 30 is held in engagement with the cam 32 by a coil spring 50 which is housed in a bore provided in the shaft 14. This spring is interposed between a nut 52 and the enlarged head 54 of a plunger 56. The nut 52 threads into the bore of the shaft 14 at the 25 rear end of the shaft. The plunger 56 is mounted for sliding movement in the bore of the shaft 14 but is held against rotation relative thereto by a key 66 that slides in a slot formed in the periphery of the head 54 of the plunger. The 30 plunger rod 56 projects rearwardly through an opening in the nut 52 and has a disc 58 secured to it by a pin 60. This disc seats against a shoulder formed on the rod 56 and is held against axial movement relative to the rod by a nut 62 35 which threads onto the rear end of the rod. A recess 72 is formed in the cap member 34 to receive the disc and nut and also to receive a disc 64 of brake or other frictional material. This disc 64 is secured in any suitable manner in the 40 recess 72 and is adapted to engage the front face of the disc 58 to exert a slight frictional pressure on the plunger 56 and, through it, on the shaft 14, resisting turning of the shaft 14. Thus a light load is applied to the shaft to insure smooth, 45 uniform rotational movement of the shaft as it is oscillated to move the diamond 10 across the outside surface of the grinding wheel. A cover plate 68 that is held to the cap member 34 by screws 70 serves to enclose the recess 72 in this 50 cap member.

The free end of the arm 31 is held in engagement with the cam 33 by a coil spring 51. This spring is mounted in a bore drilled in the shaft 15 and is interposed between one end of this bore 55 and the enlarged head 53 of a plunger or rod 55. The plunger or rod 55 is mounted in the bore of the shaft 15 to be slidably therein but is secured to rotate therewith by a key 57 which engages in a longitudinal slot formed in the head 53 of the plunger. The rear face of the head 53 of the plunger is adapted to seat against a disc 59 of suitable frictional material that is held in any suitable manner in a recess formed in a cover plate 61. This cover plate is secured to the 60 housing 20 by screws (not shown) which thread into the holes 63 (Fig. 4) tapped in the housing and it encloses the arm 31 and cam 33. The frictional disc 59 serves to put a light load on the plunger 55 and thereby on the shaft 15, to prevent vibration of the shaft 15 as it is oscillated 65 to move the dressing tool 11 across the inside surface of the grinding wheel.

The operation of the dressing mechanism of the present invention is illustrated in more detail 70 but somewhat diagrammatically in Fig. 5, with

reference to the dressing of the outside surface of a grinding wheel. The dressing tool 10, the shaft 14 which carries it, and the arm 30 which is connected to the shaft and which carries the follower, are shown in dotted lines in the positions which they occupy at one end of the movement of the dressing tool and in full lines in the positions which they occupy at the opposite end of the movement of the dressing tool. It will be seen that as the shaft 15 is rotated by movement of the piston 22, the follower will ride on the control surface of the cam 32. While the follower is in engagement with the plane portion 46 of this control surface, the point of dressing tool 11 will travel in a plane parallel to the plane surface 46 and dress a surface on the grinding wheel whose profile 40 is perpendicular to the axis of the shaft 14 and inclined to the axis of the grinding wheel at an angle determined by the position of the axis of the shaft 14. As soon as the follower begins to ride up on the inclined portion 47 of the control surface of the cam, however, the shaft 14 is moved axially, moving the dressing tool axially and a surface is then dressed on the grinding wheel whose profile 42 is less inclined to the axis of the grinding wheel, that is, of smaller pressure angle than the profile 40.

It will be obvious that by making the portion 47 of the control surface of the cam curved at its juncture with the plane portion 46, the low angle portion of the grinding wheel profile can be made to blend into the high angle portion of the profile instead of these two portions being inclined at a sharp angle to one another as shown in the drawings. It will be obvious, also, that the proportions of the profile which are of large and small pressure angle, respectively, can be varied by varying the shape of the control surface of the cam. It will be further obvious that by suitably shaping the cam, any desired shape of profile can be produced on the grinding wheel.

While the invention has been described particularly in connection with a dressing mechanism for dressing rotary annular wheels, it will be understood that it may be applied to the dressing of any form of grinding wheel. In general it may be said that the present application is intended to cover any variations, uses, or adaptations of the invention following the principles of the invention and including such departures from the present disclosure as come within known or cus-

tomary practice in the art to which the invention pertains and as may be applied to the essential features hereinbefore set forth and as fall within the scope of the invention or the limits of the appended claims.

Having thus described my invention, what I claim is:

1. Dressing mechanism comprising a support, a shaft oscillatably and slidably mounted on said support, an arm secured to one end of said shaft, a dressing tool mounted in said arm, a second arm secured to the opposite end of the shaft, a cam and a follower, one of which is secured to the second arm and the other to said support, a plunger mounted within the bore of said shaft to rotate with said shaft but to slide axially relative thereto, a coil spring interposed between the shaft and plunger to hold the follower resiliently in engagement with the cam, said plunger having an enlarged head at its rear end, means for swinging said shaft, and brake means engaging said head to apply a light frictional load on said shaft during its swinging movement.
2. Dressing mechanism comprising a support, a pair of shafts mounted in said support for rotary and axial sliding movement and having their axes inclined to one another at an angle equal approximately to the included angle between opposite sides of the wheel to be dressed, an arm secured to the front end of each of said shafts, a dressing tool mounted in one of said arms to engage one side surface of a grinding wheel and a dressing tool mounted in the other of said arms to engage the opposite side surface of said grinding wheel,
3. A follower rigidly secured to the rear end of the shaft on which the first named dressing tool is mounted, a face cam secured to said support between said follower and said arm and with which the follower is engaged, a follower rigidly secured to the rear end of the shaft on which the second named dressing tool is mounted, a face cam mounted at the rear of the latter follower to be engaged by the latter follower, each of said face cams being concentric of the shaft to which its cooperating follower is secured, means for resiliently holding the two followers in engagement with their respective cams, and a single means interposed between the two shafts for rotating the two shafts.

50

ARTHUR L. STEWART.
